FLOAT VALVE

Daniel J. Rawdon, New Hartford, Iowa, assignor to
Hawkeye Steel Products, Inc., Waterloo, Iowa

Filed Aug. 13, 1974, Ser. No. 496,933

Term of patent 14 years

Int. Cl. D23—01

U.S. Cl. D23—19

FIG. 1 is a perspective view of a float valve showing my new design;

FIG. 2 is a side elevational view thereof;

FIG. 3 is an elevational view taken from the side opposite that shown in FIG. 2;

FIG. 4 is a front elevational view thereof;

FIG. 5 is a rear elevational view thereof;

FIG. 6 is a top plan view thereof; and

FIG. 7 is a bottom plan view thereof.

I claim:

The ornamental design for a float valve, as shown.
